(57) **CLAIM**

I claim the ornamental design for a paper holder, substantially as shown and described.

DESCRIPTION

FIG. 1 is a front perspective view of a paper holder showing the present invention.

FIG. 2 is a front elevational view thereof.

FIG. 3 is a rear elevational view thereof.

FIG. 4 is a side elevational view from the left side of FIG. 1.

FIG. 5 is a side elevational view from the right side of FIG. 1.

FIG. 6 is a top plan view thereof.

FIG. 7 is a bottom plan view thereof.

FIG. 8 is a front perspective view of an alternate paper holder showing the present invention.

FIG. 9 is a rear elevational view thereof.

FIG. 10 is a side elevational view from the left side of FIG. 8.

FIG. 11 is a side elevational view from the right side of FIG. 8.

FIG. 12 is a top plan view thereof.

FIG. 13 is a bottom plan view thereof; and,

FIG. 14 is a front perspective view of the paper holder in use.

The broken lines showing a piece of paper in FIG. 14 are included for the purpose of illustrating environment and form no part of the claimed design.
